UNITED STATES PATENT OFFICE.

PATRICK H. HEALY, OF CHICAGO, ILLINOIS, ASSIGNOR TO THE AMERICAN CUT GLASS COMPANY, OF SAME PLACE.

DESIGN FOR A GLASS DISK.

SPECIFICATION forming part of Design No. 30,267, dated February 28, 1899.

Application filed December 19, 1898. Serial No. 699,758. Term of patent 7 years.

To all whom it may concern:

Be it known that I, PATRICK H. HEALY, a citizen of the United States, residing at Chicago, in the county of Cook and State of Illinois, have produced and invented a new and original Design for a Glass Disk, (Case No. 1,) of which the following is a full, clear, concise, and exact description, reference being had to the accompanying drawings, forming 10 a part of this specification.

Figure 1 is a plan view of a glass disk whereon my said design has been reproduced, and Fig. 2 is a cross-sectional view of said disk on a diameter thereof.

15 The general contour of the design is circular, while the leading or principal feature thereof is a star-shaped figure, as shown in the drawings.

20 The design herein shown is cut from the body of the glass, the several similar portions of said design being arranged in concentric circles about a central eminence *a*.

25 The twelve points of the star are formed by twenty-four splits or grooves, which, intersecting within the body of the design, form concentrically-arranged pyramids or prismatic crystals of various sizes and shapes. Thus each point of the star is formed by the 30 terminal intersection of a split *b*, cut tangent to an imaginary circle having substantially the diameter of the central eminence, and a 35 second split *c*, cut tangent to another imaginary circle having a diameter approximately three times that of the circle first named.

35 Each of the splits *b* extends from the tip or extremity of any given point of the star along one side of the interior angle of said point and terminates at the intersection *b'* of split *b* with split *c* of the third preceding point. This

intersection, it will be seen, occurs near the 40 base of the fifth point preceding that point of the star first considered. The central eminence *a* is given the form of a twelve-sided truncated pyramid, upon which six minute centrally-intersecting splits are cut. Each 45 of the prismatic bodies *d*, forming a point of the star, is fluted along a considerable portion of its upper edge, while between the points of the star fan-shaped figures *e* are formed by cutting seven small splits of different 50 lengths, which radiate from each of the outer angles of said star. The prismatic pyramids formed by the intersecting splits within the star-shaped figure are smaller and more numerous near the central portion of 55 the design, these being surrounded by others concentrically arranged and of gradually-increasing size. The points of the star when cut in this manner are inclined at a small angle away from diameters drawn through their 60 bases.

As will be seen from the accompanying drawings, the design is a beautiful and pleasing one and may be effectively reproduced in other manners than that indicated in my 65 specification and upon a large variety of manufactures, such as glass dishes, water-bottles, bowls, and the like.

I claim and desire to secure by these Letters Patent—

70 The design for a glass disk, substantially as herein shown and described.

In witness whereof I hereunto subscribe my name this 8th day of December, A. D. 1898.

PATRICK H. HEALY.
